US0D1051305S

(12) **United States Design Patent** (10) Patent No.: **US D1,051,305 S**
(45) Date of Patent: ** Nov. 12, 2024

(54) **SLEEVE**

(71) Applicant: **WOOIL FLUCON CO., LTD.**

Seongnam-si (KR)

(72) Inventors: **Da-Wun Yoo**, Seoul (KR); **Min-Ki Jin**, Gunpo-si (KR); **Ji-Hyun Kang**, Seoul (KR); **Ji-Beom Kim**, Hanam-si (KR)

(73) Assignee: **WOOIL FLUCON CO., LTD.**, Seongnam-si (KR)

(**) Term: **15 Years**

(21) Appl. No.: **29/872,978**

(22) Filed: **Mar. 23, 2023**

(30) **Foreign Application Priority Data**

Jan. 6, 2023 (KR) 30-2023-0000716

(51) LOC (14) Cl. **23-01**

(52) U.S. Cl.

USPC **D23/262**; D23/259; D23/266

(58) **Field of Classification Search**

USPC D23/207-209, 213-214, 217, 222-224, D23/229, 251, 255, 256, 259-262, 355, D23/356, 358, 360, 364-369; D8/330, D8/343, 382

CPC F16L 41/14; F16L 45/00; F16L 41/005; F16L 39/00; F16L 3/003; F16L 25/14; F16L 13/00; F16L 43/00; F16L 9/18; F16L 33/23; F16L 33/28; F16L 3/1075
